GAME BOARD

Donald A. E. Beer, 14 E. 63rd St.,
New York, N.Y. 10021

Filed Dec. 8, 1967, Ser. No. 9,708

Term of patent 14 years

U.S. Cl. D34—5
Int. Cl. D21—01

The single figure of the drawing is a plan view of the game board. An edge view is not shown since the game board is of conventional thickness.

The essential features of my design reside in the full line portions shown.

I claim:

The ornamental design for a game board, as shown and described.
